SOLDERING IRON HOLDER

Richard O. Spencer, South Laguna, Calif., assignor to
Eldon Industries, Inc., Hawthorne, Calif.

Filed Jan. 6, 1975, Ser. No. 538,533

Term of patent 14 years

Int. Cl. D8—05

U.S. Cl. D8—71

FIG. 1.

FIG. 2.

FIG. 3.

FIG. 4.

FIG. 5.

FIG. 1 is a side elevational view of a soldering iron holder embodying the new design of my invention;

FIG. 2 is a top plan view thereof;

FIG. 3 is a bottom plan view thereof;

FIG. 4 is an end elevational view of one end thereof; and

FIG. 5 is an end elevational view of the other end thereof.

The side of the soldering iron holder which is not shown of the illustrated soldering iron holder is a mirror image of the side which is illustrated in FIG. 1.

I claim:

The ornamental design for a soldering iron holder, substantially as shown and described.
